(57) **CLAIM**

The ornamental design for a WiFi amplifier, as shown and described.

DESCRIPTION

1. WiFi amplifier
1.1 is a front elevation view of a WiFi amplifier showing our new design;
1.2. is a back elevation view thereof;
1.3 is a left side elevation view thereof;
1.4 a right side elevation view thereof;
1.5 is a top plan view thereof;
1.6 is a bottom plan view thereof; and
1.7 is a perspective view thereof.

The broken lines, and surface bound on all sides by broken lines, represent features of the WiFi amplifier that form no part of the claimed design.
